UNITED STATES PATENT OFFICE.

WILLIAM A. ESKIL, OF CORONA, NEW YORK.

VALVE-TOOL.

1,382,491.

Specification of Letters Patent. Patented June 21, 1921.

Application filed March 26, 1920. Serial No. 368,978.

To all whom it may concern:

Be it known that I, WILLIAM A. ESKIL, a citizen of the United States, residing at Corona, in the county of Queens and State 5 of New York, have invented new and useful Improvements in Valve-Tools, of which the following is a specification.

This invention comprehends the provision of a tool for removing overhead valves with 10 greater ease and safety, the tool being simple in construction so that it can be manufactured and sold at a nominal cost.

The nature and advantages of the invention will be readily understood when the 15 following detail description is read in connection with the accompanying drawings, the invention residing in the construction, combination and arrangement of parts as claimed.

20 In the drawing forming part of this specification, like numerals of reference indicate similar parts in the several views and wherein:—

Figure 1 is a view in elevation of the tool 25 constructed in accordance with one embodiment of the invention.

Fig. 2 is an end elevation.

Fig. 3 is a view showing the manner of 30 using the tool.

Referring to the drawing in detail, 10 indicates the tool forming the subject matter of my invention and which tool may be constructed from any suitable material. The tool is formed with a longitudinally disposed slot 11 which opens at one end of the tool and which slot receives the valve stem 12 when the tool is in use. Depending from 35 opposite sides of the tool 10 are lugs 13 which prevent the tool from slipping off the valve when the parts are associated for use. Should the tool be constructed of wood, I provide the lower end of the tool with a metallic wear plate 14, which is secured to

the end by means of suitable fastening elements 15. The wear plate 14 is provided 45 with a central opening 16 which is disposed in alignment with the slot 11.

In Fig. 3, I have illustrated the manner of using the tool. As shown the plate 14 rests against the valve spring washer 16', 50 while this washer is engaged at opposite points by means of the lugs 13, which as above stated are provided to prevent the tool from slipping while it is being used. The valve stem 12 projects up into the slot 55 11 through the opening 15 in the plate 14. Pressure is then exerted upon the tool 10 to compress the spring 17, during which operation the valve stem 12 moves up into the slot 11 of the tool. When the pin 18 is relieved of the pressure of the spring, the pin 60 can be readily withdrawn from the valve stem, after which the tool is gradually relieved of the pressure which has been exerted thereon, until the spring 17 is fully 65 expanded. The tool is then removed from the spring and the valve can be readily taken from its position.

While I have shown and described what I consider the preferred embodiment of the 70 invention, I desire to have it understood that what is herein shown is merely illustrative, that I do not limit myself in this connection, and that such changes may be resorted to when desired as fall within the 75 scope of what is claimed.

What I claim is:—

A tool for the purpose specified comprising a body portion having a longitudinal slot opening at one end, lugs depending 80 from opposite sides of the tool and a plate secured to one end of the tool and having an opening disposed in alignment with said slot.

In testimony whereof I affix my signature. 85
WILLIAM A. ESKIL.
